DEVICE FOR EFFECTING THE THREADING
OF NEEDLES AND THE LIKE

Michael Joseph Costello, Surbiton, England, assignor of one-half to Parker Alderman, West Bexington, near Dorchester, England

Application July 18, 1947, Serial No. 761,958
In Great Britain January 27, 1947

8 Claims. (Cl. 223—99)

1

This invention relates to devices adapted to effect the threading of needles or the like, and it has for its chief object to provide such a device which, while being efficient in operation, is nevertheless simple in construction and reasonably cheap to manufacture.

In accordance with its broadest aspect, the invention resides in the provision of a device wherein the thread or the like to be threaded, is introduced thereto in such a manner as to extend transversely with respect to a guide channel or the like which is adapted to receive a needle to be threaded, and the motion of the needle as it is inserted into or withdrawn from the device, is employed to effect the operation of means whereby a portion of the thread is caused to pass through the needle eye and to form a loop which is thereafter held in such a manner that, as the needle is completely withdrawn from the device, one end of said thread will be drawn through the eye to complete the threading operation.

In further accordance with the invention, the thread or the like to be threaded is introduced into the device in such a manner as to extend transversely with respect to a guide channel or the like, which is adapted to receive a needle to be threaded, and the motion of the needle, as it is inserted into and withdrawn from the device, is employed to cause the projection and retraction through the eye thereof of an element which is adapted, during a part of its movement, to engage the thread and to carry a portion thereof through said eye to form a loop, which is thereafter held in such a manner that, as the needle is completely withdrawn from the device, one end of said thread will be drawn through the eye to complete the threading operation.

In accordance with yet a further aspect of the invention, the device includes a casing or body having a guide channel therein adapted to receive and to position a needle to be threaded, a slot or passage extending transversely with respect to the channel and into or through which a length of thread or the like to be threaded may be introduced, and means within said casing or body operative on insertion and withdrawal of a needle into and from the device to cause the projection and retraction through the needle eye of an element which is adapted, during a part of its motion, to engage the thread and to carry a portion thereof through said eye to form a loop, which is thereafter held in such a manner that, as the needle is completely withdrawn from the device, one end of the said thread will be drawn

2

through the needle eye to complete the threading operation.

In order that the said invention may be clearly understood and readily carried into effect, the same will now be hereinafter more fully described with reference to the accompanying drawings, which show the embodiments and in which:

Figure 1 is a perspective view of one embodiment of the needle threading device according to the invention;

Figure 2 is an end view of the device shown in Figure 1;

Figure 3 shows the device in side elevation one portion or half being removed for the purposes of illustration;

Figure 4 shows in perspective the portion or half complementary to that shown in Figure 3;

Figure 4a is a fragmentary section on the line 4—4 of Figure 4;

Figures 5 and 6 are views similar to that shown in Figure 3 but illustrating the operation of the device;

Figure 7 is a perspective view of a detail;

Figure 8 is a detail view showing a modification;

Figures 9—13 show a modified form of needle threading device according to the invention, Figures 9, 11, 12 and 13 being side elevational views wherein one portion of the casing or cover is removed for the purpose of better illustration of the several stages in the operation of the device, while Fig. 10 is a perspective view of a detail corresponding to that shown in Fig. 7.

Referring now to Figs. 1—7 of the drawings, it will be seen that the device comprises a casing or body made up of two complementary portions 10 and 11, which latter are adapted to be secured together by means of screws or the like indicated at 12. The portions 10 and 11 are each formed with a slot 13, the arrangement being such that

when said portions are secured together, the two slots will be aligned and will provide a single slot or passage which extends transversely of the casing or body and which will allow of the introduction of a length of cotton, thread or the like thereto. The portions 10 and 11 are also relatively so formed as to provide a longitudinally extending slot 14 therebetween, said latter slot being adapted to communicate with the transverse slot 13 and to extend therefrom to that end of

the casing or body into which needles to be threaded are inserted. The inner face of the portion 10 is also formed with a longitudinally extending channel 15 with which the slot 14 is also adapted to communicate, said channel being so dimensioned as to accommodate a needle

and to form a guide channel into which a needle to be threaded may be inserted. As indicated in the drawings, the channel 15 is preferably so formed that when the device is held so that the walls of the slot 14 are vertical, the top wall 15a of said channel will be horizontal while the other wall will be inclined downwardly at an angle relatively thereto. Preferably also the portions 10 and 11 are suitably recessed or cut away as indicated at 16 to form guide surfaces and to facilitate insertion of the needle into the channel 15.

The internal face of the portion 10 is also formed with a recess 17 with which the channel 15 is adapted to communicate, said recess being adapted to accommodate a member 18 which is mounted in any convenient manner for pivotal movement about a point designated 19. The member 18, a slightly modified form of which is shown in Figure 7, is formed with a projecting portion 20 so dimensioned as to project into the path of any needle inserted through the channel 15, said projecting portion being formed with a V-shaped recess 21, the purpose of which will be hereinafter made apparent. The member 18 is also adapted to carry a hook element 22 which is so dimensioned as to be adapted to be projected through the eye of any needle which may be introduced into the channel 15. The hook element 22 may conveniently be made of fine wire which, while possessing a degree of resilience, is nevertheless sufficiently rigid to be proof against deformation when in use but, if desired as indicated in Figure 7, said element may be made of any other suitable material being mounted in a slot or the like in the member 18 and secured in position by one or more screws, such as are indicated at 221, in such a manner as to be readily removable and replaceable. The member 18 is normally urged forwardly into the position shown in Figure 3 by means of a spring 23, which may be of any convenient form other than that shown, and may be anchored in any suitable manner. Also, suitably mounted within the portion 10, is a further leaf spring 24 which is so constructed and arranged as to co-operate with a needle inserted into the channel 15 and in conjunction with said channel and a spring 25 in the portion 11 to ensure correct positioning of the needle within the device. The spring 24 is formed with a flattened portion 24a adapted to constitute a resilient platform and to co-operate with a needle to ensure correct positioning thereof. The spring 25, which is in the form of a leaf spring, may be mounted in the portion 11 in any convenient manner, being so disposed that on assembly of the two portions 10 and 11, it will lie opposite the channel 15. As will be apparent from Figure 4, the interior face of the portion 11 is also formed with a recess or the like 26 adapted, when said portion is applied to the portion 10, to be aligned with the recess 17 in the latter, and together therewith, to form a space such as will accommodate the working parts of the device.

In order to operate the device, the head of a needle to be threaded is inserted into the channel 15. On initial insertion of the needle into the channel 15, it will be pressed by the spring 25 towards the narrowest part or apex of said channel. As all needles are slightly flattened at the head in the area of the eye, the needle will be caused automatically to assume a position such that on further insertion, the flattened portion thereof will be engaged by the flat portion 24a of the spring 24 and will be pressed against the wall

15a of the channel 15. The action of the springs 24 and 25, in conjunction with the formation of the channel, causes the needle to be turned into such a position that, upon complete insertion, the eye will lie in a plane such that the hook element 22 may be projected therethrough. Due to the particular construction of the channel 15 and to the pressure of the springs 24 and 25, it is immaterial how the needle is inserted into the device, since on being pushed into the channel 15, it will be automatically guided into the correct position to allow of the subsequent projection of the hook element 22 through the eye thereof. It will be apparent from Figure 5 that, as the needle is pushed into the device past the spring 24, it will contact with the projecting portion 20 of the member 18 and will cause the latter to be moved about its pivot 19 against the action of the spring 23. At a predetermined point in the movement of the member 18, the hook element 22 will be projected into the eye of the needle, and when the latter is fully inserted as shown in Figure 3, said element will be projected completely through said eye. Due to the V-shaped recess 21 in the projecting portion 20, the head of the needle will be caused automatically to assume a central position so that the eye will always be correctly aligned with the hook element 22. When the needle is fully inserted, the end portion of the cotton or the like to be threaded is passed across the slot 13 and is drawn towards the base thereof. As will be seen from Figure 5, when the cotton or thread, which is designated by 27, is in position in the slot 13, it will extend across the needle, and as the latter is withdrawn from the device, the member 18 will be moved in the opposite direction about its pivot towards its initial position illustrated in Figure 3, due to the co-operation between the hook element 22 and the needle eye, and also to the action of the spring 23, thereby causing said hook element to be progressively withdrawn from the needle eye. As the hook element 22 is withdrawn, it will engage the cotton or thread 27, and will draw the same through the needle eye as indicated in Figure 6, the free end of the cotton or thread being drawn through said eye to complete the threading operation as the needle is fully withdrawn from the device.

In the event of the thread being attached to a garment or the like, when the needle threading operation is completed and the needle is withdrawn from the device, the latter may be disengaged from the thread by virtue of the provision of the slot 14, which allows said device to be pulled away or withdrawn from said cotton or thread.

If the hook element 22 is formed of wire or other material possessing a degree of resilience, the device above described and illustrated may be employed to thread needles of differing types and sizes, but in certain cases it may be desirable so to mount said hook element that it is capable of slight angular adjustment with respect to the member 18 to ensure that it may be projected through the eye of any needle introduced into the device, despite variations in the actual position of said eye with respect to the head of the needle. For example, in the embodiment shown in Figure 7, the holes in the hook element through which the securing screw or screws 221 pass may be slightly enlarged to allow for slight variation in the position of said element.

Preferably two stops 18a and 18b are provided within the recess 17 for the purpose of limiting

the extent of the pivotal movement of the member 18. The stop 18a is adapted to limit the extent of movement of the member 18 under the action of a needle inserted into the device, thereby preventing any overriding of the hook element, the subjection of said element to strain when projected through the needle eye, and also any excessive compression of the spring 23 such as would result in weakening of the same. The stop 18b is adapted, on return of the member 18 to its initial position, to keep the hook element in the closed position when it is made of material other than wire, and is so mounted that slight movement thereof is allowed for in the manner indicated above. The stops may be formed of metal or other suitable material, and mounted within the recess 17, or they may be formed integrally with the casing portion 10.

Instead of forming the guide channel 15 in the portion 10 and providing the springs 24 and 25 it may be feasible to adopt a construction such as that shown in Figure 8. Referring now to that figure, it will be seen that the portion 10 is formed with an enlarged slot or cut away portion 39 of substantially rectangular section in which a spring pressed platform 31, is disposed. The platform 31 which as shown in the figure, is urged upwardly by a spring 32 and is formed with a chamfered or bevelled surface 33 adapted, in conjunction with the upper wall of the slot 30, to form a channel of substantially the same form in cross section as the channel 15 in the preceding figures. The chamfered or bevelled surface 33 is merged at its inner end into a flat platform 34, which is adapted to serve the same purpose as the flattened portion 24a of the spring 24. It will be appreciated that, as the needle is inserted into the channel formed by the surface 33 and the upper wall of the slot 39, it will be turned into a position such that, on further insertion, the flattened portion of the needle will be pressed by the platform 34 flat against said upper wall, thereby ensuring that the eye of the needle will be correctly positioned to receive the hook element.

In the embodiment above described, the introduction of the thread into the device is effected after complete insertion of the needle, and said thread is drawn through the needle eye by means of the hook element 22 on retraction of said needle. In Figures 9-13, a slightly modified construction is shown wherein the thread is pushed through the needle eye to form a loop during insertion of the needle into the device, the completion of the threading operation being effected on subsequent withdrawal of said needle. The device illustrated in Figures 9-13 is similar in most respects to that above described with reference to Figures 1-7, and comprises a casing or body made up of two complementary portions, which are adapted to be secured together by means of screws or the like. In Figures 9, 11, 12 and 13, only one portion 35 corresponding to the portion 10 is shown, such portion including a slot 36 corresponding to the slot 13 and adapted to allow for the introduction of thread into the device, and a channel 37 corresponding to the channel 15, said channel 37 constituting a guide channel into which a needle to be threaded may be inserted. The formation of the channel 37 is similar to that shown in Figures 1-7, so that correct positioning of the needle may be assured. The inner face of the portion 35, as the case of the portion 10, is formed with an internal recess 38 adapted to accommodate a member 39 which is mounted in any convenient manner for pivotal

movement about a point 40. The member 39, as is the case with the member 18 in the preceding embodiment, is formed with a projecting portion 41 so dimensioned as to project into the path of any needle inserted into the channel 37, such projecting portion being formed with a V-shaped recess 42, the purpose of which is similar to that of the recess 21 in the member 18. The member 39 is adapted to carry a forked bar or prong 43, which may be mounted in position therein in any convenient manner, so that the forked or operative end of said bar or prong will project into the recess 42, and will be aligned with a further slot or recess 44 formed in the rear face of the projecting portion 41 of the member 39. The construction and arrangement of the various parts is such that, when the member 39 is in its inoperative position as shown in Figure 9, the slot 44 will be aligned or in register with the slot 36. As is the case with the member 18, the member 39 is normally urged forwardly into the position shown in Figure 9 by means of a spring 45, corresponding to the spring 23, which may be of any convenient form other than that shown, and may be anchored in any suitable manner. Preferably, stops 39a and 39b are incorporated in the device to co-operate with the member 39, such stops serving the same purpose as the stops 18a and 18b in the embodiment above referred to. Also mounted within the recess 38, is a spring 46 similar to, and serving the same purpose as, the spring 24 of the preceding embodiment, while in addition, a spring fork or the like 47 is disposed adjacent the path of movement of any needle inserted into the device, the purpose of said fork or the like being hereinafter made apparent. The other half of the casing or body is identical with that shown in the preceding embodiment, having a slot corresponding to the slot 13, an internal recess corresponding to the recess 26, and a spring corresponding to the spring 25.

The operation of the embodiment shown in Figures 9-13 is as follows: A portion of the thread to be threaded is first introduced into the slot 36 and, as indicated above, the construction and arrangement of the various parts is such that said thread, which is designated at 48, will enter the slot 44 in the projecting portion 41 of the member 39 and will be disposed transversely with respect to the forked bar or prong 43. When the thread 48 is in position, the needle to be threaded is introduced into the channel 37 and, owing to the special formation of such channel and the action of the spring 46 and the spring in the other half of casing or body (not shown), said needle will be turned automatically into such a position that, on continued insertion, the forked bar or prong 43 will be projected through the needle eye. As in the preceding embodiment, the head of the needle will contact the projecting portion 41 of the member 39 and will cause the latter to be moved about its pivot against the action of the spring 45. At a predetermined point in the movement of the member 39, the forked bar or prong 43 will be projected through the eye of the needle, carrying with it a portion of the thread. As in the preceding embodiment, due to the V-shaped recess 42 in the projecting portion 41, the head of the needle will be caused automatically to assume a central position so that the eye will always be correctly aligned with the bar or prong 43. When the needle is fully inserted, as shown in Figure 11, the construction and arrangement of the various parts is such that the bar or prong will be pro-

jected through the needle eye a distance such that sufficient thread will be pushed through said eye to form a loop. As the needle is retracted from the fully inserted position, the member 39 will commence its return movement to its initial position under the action of the spring 45, and the forked bar or prong 43 will be retracted from the needle eye, as illustrated in Figure 12 leaving a loop of thread projected through said eye. Upon continued retraction of the needle, the bar or prong 43 will be completely withdrawn from the needle eye and the loop of thread remaining will be engaged by the spring fork or the like 47, as shown in Figure 13. The fork 47 serves to hold the thread so that upon further or complete withdrawal of the needle from the device, one end of said thread will be drawn through the needle eye and the threading operation will thereby be completed.

In the event of the thread being attached to a garment or the like when the needle threading operation is completed and the needle is withdrawn from the device, the latter may be disengaged from the thread by virtue of the provision of a slot equivalent to the slot 14, which allows said thread to be pulled away or withdrawn from said device.

If the bar or prong 43 is formed of material possessing a degree of resilience, the device may be employed to thread needles of different types and sizes but in certain cases, it may be desirable so to mount said bar or prong that it is capable of slight angular movement with respect to the member 39 to ensure that it may project through the eye of any needle introduced into the device, despite variations in the actual position of said eye with respect to the head of the needle. For example, the bar or prong may be secured in position similarly to the hook element shown in Figure 7, the holes therein, through which the securing screws are adapted to pass, being slightly enlarged to allow for slight variations in the position of said element.

As with the preceding embodiment, it may be desirable in certain cases to adopt a construction such as that shown in Figure 8, and thereby to dispense with the special formation of the guide channel 37, and with the spring 46, and the spring in the other half of the casing or body.

The portions constituting the components of the casing or body of either of the foregoing embodiments of the device may be formed of any convenient material such as wood, metal or synthetic resin or the like and they may be of any convenient shape or configuration other than that illustrated.

Preferably, means are associated with said casing or body to allow of attachment of the device to a convenient point on a garment of the person using the same. For example, as illustrated in Figure 1, a ring 28, to which a cord or the like having a safety pin or other convenient fastening device associated therewith may be attached, may be inserted through that end of the casing or body from the operative end of the device, or a tab or the like having a button-hole or other suitable device may conveniently be employed. Furthermore, the device may in certain cases be mounted on and/or form part of an article equipment for use in a tailor's or seamstress's workroom or the like. For example, it may be mounted on, or formed integrally with, a support or pillar projecting upwardly from a pin or other tray, which may also be equipped with

means for holding reels, or spools of cotton or the like.

The device according to the invention may be constructed in varying sizes to accommodate any size or type of needle from a very fine needle, such as is used with the finest cotton, to a large needle adapted to be threaded with wool or other relatively thick material, each size being capable of effecting the threading of a selected range of sizes of needles, and it has the advantage that, since it is not necessary to insert the needle into the device in any preselected position, it can be used by anyone whether in possession of sight or not with a certainty of operation.

I claim:

1. A needle threader comprising a body having an internal chamber, a needle guide channel in said body communicating with said chamber, a slot in said body for the reception of thread also communicating with said chamber and extending transversely with respect to said guide channel, means in said guide channel adapted to turn a needle inserted thereinto about its longitudinal axis and to bring the eye into a predetermined position, a member mounted for pivotal movement within said chamber, said member having a portion projecting into the path of a needle inserted into the guide channel, a thread engaging member fixedly mounted on said pivoted member, the arrangement being such that on insertion of a needle into the device a pivotal movement will be imparted to said pivoted member by the needle to cause said thread engaging member to be projected through the needle eye said thread engaging member being retracted on reverse movement of said pivoted member resultant upon withdrawal of the needle so that with a length of thread inserted into said transverse slot, said thread engaging member during a part of its motion will engage the thread and carry a portion thereof through the needle eye to form a loop which is thereafter held in such a manner that as the needle is completely withdrawn from the device, one end of said thread will be drawn through the needle eye to complete the threading operation.

2. A needle threader as claimed in claim 1, further including a longitudinally extending slot in said body communicating with said chamber and said first-mentioned slot for permitting release of the threader from the thread after the needle has been threaded and withdrawn from the threader when the thread is attached to a garment or the like.

3. A needle threader comprising a body having an internal chamber, a needle guide channel in said body communicating with said chamber, a slot in said body for the reception of thread also communicating with said chamber and extending transversely with respect to said guide channel, means in said guide channel adapted to turn a needle inserted thereinto about its longitudinal axis and to bring the needle eye into a predetermined position, a member mounted for pivotal movement within said chamber, said member having a portion adapted to project into the path of the needle inserted into the guide channel, a hook element rigidly secured on said member to pivot therewith, said hook element being so positioned that on insertion of a needle into the guide channel and consequent pivotal movement of said member and hook element, the hook element will be projected automatically through the needle eye to engage a thread subsequently introduced into the transverse slot.

4. A needle threader comprising a body having an internal chamber, a needle guide channel in said body communicating with said chamber, a slot in said body for reception of the thread also communicating with said chamber and extending transversely of said guide channel, means in said guide channel adapted to turn a needle inserted thereinto about its longitudinal axis and to bring the needle eye into a predetermined position, a member mounted for pivotal movement within said chamber, said member having a portion adapted to project into the path of the needle inserted into the guide channel, means associated with said member and adapted to return the same to its initial position after withdrawal of the needle, and a hook element mounted on said member to pivot therewith, said hook element being so positioned that on insertion of a needle into the guide channel and consequent pivotal movement of said member and hook element, the hook element will be projected automatically through the needle eye to engage a thread subsequently introduced into the transverse slot.

5. A needle threader comprising a body having an internal chamber, a needle guide channel in said body communicating with said chamber, a slot in said body for the reception of thread also communicating with said chamber and extending transversely of said guide channel, a member mounted for pivotal movement within the chamber, said member having a portion adapted to project into the path of a needle inserted into said guide channel, said portion having a V-shaped guide recess therein adapted to position the needle head, a spring associated with said member adapted to return the same to its initial position after withdrawal of the needle, a hook element mounted in said member to pivot therewith, and means within said guide channel for positioning any needle inserted thereinto so that

the eye thereof will be positioned to allow the hook element to be projected automatically therethrough on movement of the pivotal member and hook element under the action of said needle.

5 6. A needle threader as claimed in claim 5 in which the means in the guide channel comprise a resilient member adapted to co-operate with a needle inserted into said channel, the latter 10 being so formed that due to the action of said resilient member correct positioning of the needle will be ensured.

7. A needle threader as in claim 5 in which the means in the guide channel comprise a longitudinally extending platform, resilient means 15 adapted to support said platform which is formed with a bevelled surface adapted in conjunction with a wall of the guide channel to effect correct positioning of the needle.

20 8. A needle threader as claimed in claim 5 in which the body comprises two complementary portions, and means for securing said portions together.

MICHAEL JOSEPH COSTELLO.
